[57] CLAIM

An ornamental design for boat handling slots, as shown and described.

DESCRIPTION

FIG. 1 is a perspective view of boat handling slots showing my new design, said perspective view being generally from a top side of a boat illustrated by dashed lines;

FIG. 2 is a top plan view of my new design with the boat illustrated by dashed lines; and,

FIG. 3 is an enlarged perspective view of one of said boat handling slots of my new design.

The dashed lines are for illustrative purposes only to show the general location of boat handling slots with respect to the boat and form no part of the present design.
